UNITED STATES PATENT OFFICE.

LEOPOLD KAHN, OF NEW YORK, N. Y.

DESIGN FOR AN ORNAMENTAL METAL SHEET.

SPECIFICATION forming part of Design No. 22,625, dated July 18, 1893.

Application filed April 8, 1893. Serial No. 469,610. Term of patent 3½ years.

To all whom it may concern:

Be it known that I, LEOPOLD KAHN, of New York city, in the county and State of New York, have invented a new and original Design for an Ornamental Metal Sheet for Decorative Purposes, of which the following is a full, clear, and exact specification.

My design relates to an ornamental sheet for decorative purposes such as is used in the embellishment of bottles, vases, or flat surfaces, such as on frames and like articles.

Reference is to be had to the accompanying drawing, forming a part of this specification, which displays the novel design.

The essential features of my design, comprise the fern fronds A, laterally curved in the same direction, the intervening, meshed lace-like effects B, the ornamental marginal band C, at the lower edge of the fabric, the

arched fern fronds D, appearing below the large fern fronds A, and the smaller intervening fern leaves E, that are curved oppositely from the fronds A; there being curved tops of fern leaf branches F, displayed between the curved upper portions of the large fronds A, all the leaves having a waving appearance, and touching at edges in numerous points, producing a graceful, chaste, and beautiful design for the purpose indicated.

I claim—

The design for an ornamental metal sheet for decorative purposes substantially as set forth.

LEOPOLD KAHN.
